UNITED STATES PATENT OFFICE.

ADOLPH F. STOELTING, OF KIEL, WISCONSIN, ASSIGNOR TO STOELTING BROTHERS COMPANY, OF KIEL, WISCONSIN, A CORPORATION OF WISCONSIN.

CHEESE HOOP.

Application filed September 16, 1921. Serial No. 501,064.

To all whom it may concern:

Be it known that I, ADOLPH F. STOELTING, a citizen of the United States, and resident of Kiel, in the county of Manitowoc and State of Wisconsin, have invented certain new and useful Improvements in Cheese Hoops; and I do hereby declare that the following is a full, clear, and exact description thereof.

10 My invention relates to a new and useful improvement in cheese hoops and more particularly of that type which are used in making Longhorn cheeses.

15 The general object of the invention is to provide a structure whereby the clamping action between the ring and hoop is most effective at the point where the lower edge of the ring engages the shoulder of the hoop whereby to prevent wrinkles being formed 20 in the bandage at the upper portion of the cheese where such wrinkles are most likely to occur.

25 A further object of the invention is to provide a hoop to which the ring may be more readily applied without disarranging the bandage. My invention will be described in connection with the accompanying drawing, in which;—

30 Figure 1 is an elevational view with the upper portion of the device shown in section, and

Figure 2 is a fragmentary sectional view showing a modified form of the invention.

In the drawing the numeral 5 indicates the 35 hoop which is usually formed with a slight taper toward the lower end and is provided with the enlarged portion 6 which is connected with the lower portion of the hoop by a shoulder 7 against which the lower edge of 40 the hoop 8 engages to clamp the bandage 9 in position to receive the curd. The greater part of the upper portion 6 is formed in the present instance of somewhat larger diameter than has heretofore been customary and 45 is connected with the shoulder 7 by a sloping portion 10 against which the lower edge of the ring is tightly clamped to hold the bandage.

In the modification shown in Figure 2 instead of having the sloping portion 10 in the hoop the lower portion of the ring is out-

wardly flared as shown at 11 to accomplish the same purpose of tightly engaging the bandage.

It will readily be understood that in using 55 the hoops heretofore constructed the pressure between the ring and hoop is distributed throughout the entire surface of the upper portion 6 and consequently the clamping action is not particularly effective at any given 60 point. On the other hand in a hoop constructed in accordance with my invention a firm and positive clamping action is secured against the shoulder. It will also be understood that the ring may be quickly applied so 65 as to pull the bandage tight at the point where it is clamped and straighten out any wrinkles which might have a tendency to form.

I claim as my invention:

1. A device of the character described comprising a hoop formed with an annular shoulder around the interior thereof and a ring adapted to seat on said shoulder, the upper portions of the ring and hoop being 75 slightly spaced and substantially equidistant at all points when the ring is seated, and said ring and hoop converging toward each other immediately above said shoulder so as to clamp a bandage therebetween. 80

2. A device of the character described comprising a hoop formed with an annular shoulder around the interior thereof and a ring adapted to seat on said shoulder, the portion of the hoop immediately above the 85 shoulder being tapered toward the shoulder so as to closely engage the ring to clamp the bandage therebetween.

3. A device of the character described comprising a hoop formed with an annular 90 shoulder around the interior thereof and a ring adapted to seat on said shoulder, the lower portion of the ring being flared so as to closely engage the interior of the hoop adjacent the shoulder to clamp the bandage 95 therebetween.

In testimony that I claim the foregoing I have hereunto set my hand at Kiel, in the county of Manitowoc and State of Wisconsin.

ADOLPH F. STOELTING.
